UNITED STATES PATENT OFFICE.

WILLIAM L. CRAIG, OF EMERYVILLE, CALIFORNIA.

SIGNALING DEVICE.

Application filed September 27, 1924. Serial No. 740,367.

My invention is an improved vehicle signal, the prime object being to provide a slideable panel back of an opening in the signal so that different colored lights are provided 5 at different positions of the signal.

Another object is to provide a signal which is positioned on both sides of the vehicle so that it may be seen from any position at the front or rear of the vehicle.

10 In the annexed drawing in which my invention is illustrated,

Figure 1 is a front elevation of my signals in position on the vehicle.

15 Figure 2 is a fragmentary side view of the signal actuating mechanism.

Figure 3 is an enlarged sectional view taken on the line 3—3 of Figure 2.

Figure 4 is an enlarged sectional view taken on the line 4—4 of Figure 2.

20 Figure 5 is a longitudinal sectional view of the signal.

Referring more particularly to the drawings, the vehicle 1 has hollow windshield supporting brackets 2 secured thereto, from 25 which arms 3 extend upon each of which my signal 4 is pivoted. The signal comprises an elongated hollow housing having openings 5 formed in the side thereof and over which openings a transparent slide 6 is positioned.

30 These slides operate in guides 7—7 within the signal. These transparent slides 6 are formed in two sections, the inner half being red and the outer half being green or blue, as shown at 8 and 9.

35 Thus it will be seen that when the signal is elevated to indicate a right turn, the slide 6 will move inwardly under the force of gravity bringing the green section over the opening 5 to indicate a free passage on the left side of the vehicle.

40 In the lower positions of the signal indicating stop or left turn, the red portion of the slide is over the opening indicating danger.

A suitable light 10 is mounted within the 45 signal and is supplied with current through suitable conduits 11 extending through the hollow brackets 2. The signal may be actuated in any desired manner such as a rod 12 secured to the steering column 13 and 50 rotated by a handle 14. A disc 15 is secured to the rod 12 and cables 16—16 are secured

thereto and extend outwardly over suitable pulleys and through the brackets 2 and arms 3 and are secured to the signal 4. Thus it will be seen that as the handle 14 is rotated 55 the signals 4 will be swung upwardly into signaling position. A contact plate 17 is mounted adjacent the rod 12 and a contact finger 18 is secured to said rod and engages various contact points 19 on the contact 60 plate 17.

The contact points 19 are mounted in countersunk holes in the contact plate 17 so that the top of the points 19 are slightly below the surface of plate 17. The finger 18 65 is made of spring material and the point of finger 18 drops into the depressions thus formed and makes contact with points 19 as it is rotated during the operation of the device. As the points pass through the depressions the increased friction is felt by the 70 operation of handle 14 thus enabling the operator to feel the different positions of the handle and arm.

The contact points 19 being spaced in 75 proper relation with the three positions of the arms 4 allow the signal to be illuminated only when the finger rests on the point corresponding to the desired position of the signal arm—thus eliminating confusion of 80 the signals at night.

The electric wire 11 extends from the contact plate 17 to the lights 10 in the signals. Thus it will be seen that as the handle 14 is rotated, the lights will be lit to illuminate 85 the signal.

The outer end of the signals 4 is opened to permit light to shine therein and to fall upon the fingers 20—20 projecting from the end of said signal.

90 Having described my invention, I claim:
A vehicle signal comprising a hollow arm having a lamp therein and formed with an opening and a window pane slideable over said opening, the latter having sections of 95 different colors and responding to tilting motions of the arm so as to display different colors for upward and downward tilting motions of the arm.

In testimony whereof I affix my signature.

WILLIAM L. CRAIG.
